UNITED STATES PATENT OFFICE.

BENJAMIN T. HEADLEY AND DAVID IRVIN DU BOIS, OF MILLVILLE, NEW JERSEY,
ASSIGNORS TO WHITALL-TATUM COMPANY, OF MILLVILLE, NEW JERSEY, A COR-
PORATION OF NEW JERSEY.

DELIVERY MECHANISM.

1,425,962.

Specification of Letters Patent. Patented Aug. 15, 1922.

Application filed March 28, 1921. Serial No. 456,083.

To all whom it may concern:

Be it known that we, BENJAMIN T. HEADLEY and DAVID IRVIN DU BOIS, both citizens of the United States, residing at Millville, in 5 the county of Cumberland and State of New Jersey, have invented a new and useful Improvement in Delivery Mechanism, of which the following is a full, clear, and exact description.

10 An important object of the present invention is to automatically remove the vials or blanks from a machine which has performed an operation thereon, and maintain the same in such relative positions that portions 15 of different temperatures are prevented from coming into contact.

Another object of the invention is to automatically receive vials or blanks from a vial working machine, and retain the same until 20 the temperature conditions are such that the vials can be conveniently handled.

Still another object of the invention is to provide a mechanism for receiving, transferring, and delivering vials without any 25 undue breakage losses.

A further object of the invention is to provide a mechanism of the character referred to, which may be readily adjusted to accommodate vials of different lengths, and 30 which may be readily applied to the machine in connection with which it is used.

The foregoing and other objects of the present invention, together with their attendant advantages, will be apparent as the 35 invention becomes better understood by reference to the accompanying specification and drawings forming a part thereof, it being premised that changes may be made in the various details and manner of operation 40 within the scope of the appended claims without departing from the spirit of the invention.

In the drawings:—

Figure 1 is a vertical sectional view on the 45 line I—I of Figure 2, illustrating the delivery mechanism in operative relation to a vial working machine;

Figure 2 is a front view of the mechanism illustrated in Figure 1;

50 Figure 3 is a transverse sectional view, on

an enlarged scale, on the line III—III of Figure 1;

Figure 4 is a vertical sectional view on an enlarged scale, and partly broken away, on the line IV—IV of Figure 2; and

55 Figures 5 and 6 are detail perspective views of different portions of the mechanism.

At the present time it is customary to make vials from tubular blanks each of which has a length slightly greater than 60 twice the length of the finished vial. These blanks are fed to a mechanism for producing necks thereon, if necks in the finished articles are desired, and then fed to a mechanism for heating the necked blanks at their 65 central portions, dividing the same, and then forming bottoms thereon. When unnecked vials are desired, the blanks are fed directly to a bottoming machine without first being subjected to a necking operation. It will be 70 apparent that as the finished vials leave the bottoming mechanism they are considerably hotter at the bottom ends than at the neck ends, and it is essential in order to prevent cracking and breaking of the vials, to prevent the hot ends of the different vials from 75 coming into contact with the cold ends of other vials. At this time also, the vials are too hot to be conveniently handled manually,

so that it is desirable to retain the same in 80 the mechanism until a partial cooling has been effected. The present mechanism is adapted to advantageously and automatically take the finished vials from the bottoming machine, keep the same in a definite relation, and retain the same until the desired cooling has been effected.

85 Referring more particularly to Figure 1, there is illustrated a portion of the frame 2 of a vial bottoming machine, having journaled therein in a transversely extending shaft 3 carrying any desired number of similar sprocket wheels 4. Adapted to be moved by these sprocket wheels, are endless carriers 5, preferably in the form of endless chains, 90 upon which are blank supports 6 carrying rollers 7 for the vial blanks B. It will be 95 apparent that the shaft 3 may be operated in any desired manner to subject the vial blanks to the proper operations in the bot- 100

toming machine. The specific construction of the bottoming machine forms no part of the present invention, but is described and claimed in co-pending application Serial No. 5 338,179, filed November 15, 1919. In Figure 1 of the drawings, there is illustrated that portion of the bottoming machine which may be termed the delivery portion, at which the finished vials are adapted to be transferred to a packing or storing room.

According to the present invention, there is attached to the delivery end of the bottoming machine a transfer mechanism for the finished vials. This mechanism may 15 comprise a series of transversely extending bars 8 secured at their opposite ends to portions of the frame 2 of the bottoming machine. Each of these bars has secured thereto a plurality of vertically extending guide 20 strips 9, preferably mounted in spaced relation. Cooperating with each of the transversely extending bars 8 are transversely extending angles 10, also having their ends secured in any desired manner to the frame 25 of the bottoming machine, and carrying at their inner ends U-shaped bars 11. Secured to the bars 11, in opposed relation to the guide strips 9, are guide strips 12. In order to permit variation or adjustment 30 in the position of the guide strips, the U-shaped bars 11 are preferably each provided with a series of vertically extending slots 13 cooperating with bolts 14 extending therethrough, as clearly shown in Figure 35 4. To permit further adjustment of the U-shaped bars to accommodate the delivery mechanism to vials of different diameters, the inner ends of each of the transversely extending angles 10 are provided with slots 40 15 through which extend the bolts 16 connected to the U-shaped bars. Due to this construction, it will be apparent that the relative positions of the guide strips may be adjusted as desired to accommodate the 45 mechanism to the vials being operated upon. At their upper ends, the guide strips 9 are curved rearwardly into such position that they cooperate with the supports 6 to receive the vials B therefrom as the carriers 5 are 50 moved. The guide strips 12 also have their upper ends curved rearwardly to form guards 17 preventing the vials from leaving the guide strips 9. At their lower ends, the sets of guide strips are both curved in 55 the opposite direction, the ends of the strips 9 being extended beyond the termination of the strips 12 to form an open topped pocket 18.

For cooperating with the ends of the vials 60 as they are received from the bottoming machine, the transversely extending bars 8 carry fixed gauge strips 19 converging at their upper ends, as clearly illustrated in Figure 2. Cooperating with the gauge 65 strips 19 are gauge strips 20 carried by ad-

justable brackets 21, whereby the distance between the gauge strips may be varied to accommodate vials of different lengths. At their upper ends the gauge strips 20 diverge to provide gradually flaring portions for the 70 reception of the vials from the bottoming machine.

Secured in any desired manner to the frame 2 of the bottoming machine, adjacent the opposite sides thereof, are upwardly 75 projecting bearings 22 in which is journaled a transverse rock shaft 23. Secured to the rock shaft 23 in such position as to extend between adjacent pairs of guide strips, as clearly shown in Figure 2, are curved stripping fingers 24. For holding these fingers in such position that the vials may pass freely into the storage and cooling chambers formed by the guide strips and gauge strips, there is secured to the shaft 23 an 80 arm 25 to the lower end of which is attached one end of a tension spring 26 having its opposite end attached in any desired manner to the frame of the bottoming machine. For rotating the rock shaft in a clockwise 85 direction, as viewed in Figure 4, against the action of the spring 26, there is provided a crank arm 27 cooperating with a link 28, the opposite end of which is pivotally connected to a plunger 29 reciprocably 90 mounted in one of the bearings 22. At its inner end, the plunger 29 is provided with an antifriction roller 30 adapted to bear against the cam face 31. This cam face may be secured in any desired manner to 100 one end of a longitudinally extending shaft 32 of the bottoming machine, which may be operated in timed relation to the movement of the shaft 3 and carriers 5. Due to this construction, it will be apparent that as the 105 shaft 32 rotates it will bring different portions of the cam face 31 successively into engagement with the antifriction roller 30, thereby reciprocating the plunger 29 and oscillating the curved stripping finger 24. 110 This finger will cooperate in turn with the vials B, which have left the supports on the endless carriers, and have passed into the storage and cooling chambers of the delivery mechanism, and will push the same toward 115 the discharge end of said chambers.

In order to prevent the too rapid movement of the vials through the storage and cooling chambers, the guide strips 12 may be provided at any desired points along their 120 length with inwardly projecting spring fingers 33 acting to restrict the movement of the vials until their resiliency is overcome by the weight of the accumulated vials thereabove. In actual operation, it has been 125 found desirable to first fill each of the storage and cooling chambers manually before starting the bottoming machine, although such action is not essential.

It will be obvious that the construction of 130

the fixed gauge strips 19 is such that they tend to separate adjacent vials which have just been produced from a common blank, by engagement with the freshly formed heated bottom portions thereof. At the same time, the cooler necked ends of the vials are prevented from coming into contact with the hotter bottom ends, and cracking is thereby avoided. By the time the finished vials have traveled through the storage and cooling chambers in the delivery mechanism, they are cooled to such an extent that they may be conveniently handled. If desired, there may be placed below the pocket 18 formed by the lower ends of the guide strips 9, a receptacle of any desired construction into which the blanks will be automatically discharged as fresh blanks are received by the upper end of the mechanism.

The advantages of the present invention arise from the construction facilitating handling of the newly formed vials whereby portions of different temperatures are maintained out of contact.

Further advantages of the invention arise from the provision of elongated storage and cooling chambers permitting a substantial cooling of the vials before they are discharged therefrom.

We claim:

1. A delivery mechanism for vial working machines, comprising guide members forming a storage and cooling chamber, and means for transferring the vials from the vial working machine to said chamber, substantially as described.
2. A delivery mechanism for vial working machines, comprising guide members forming cooperating storage and cooling chambers, and means for transferring vials from the vial working machine into said chambers, substantially as described.
3. A delivery mechanism for vial working machines, comprising adjustable guide members forming a storage and cooling chamber, and means for transferring the vials from the vial working machine into said chamber, substantially as described.
- 50 4. A delivery mechanism for vial working machines, comprising guide members and gauge members forming a storage and cooling chamber, means for adjusting certain of said members, and means for transferring the vials from the vial working machine into said chamber, substantially as described.

55 5. The combination with a vial working machine having means for carrying finished vials, of a delivery mechanism comprising a series of guide strips forming a storage and cooling chamber and having their upper ends formed to cooperate with said means, substantially as described.

65 6. A delivery mechanism for vial working

machines, comprising a series of opposed guide strips, means for adjusting the position of certain of said strips, a plurality of gauge strips cooperating therewith, and means for adjusting the position of certain 70 of said gauge strips, substantially as described.

7. A delivery mechanism for vial working machines, comprising guide strips for engagement with the sides of the vials, and 75 gauge strips for engagement with the bottoms of the vials, said gauge strips having their upper ends converging to engage and separate the heated ends of the vials, substantially as described.

8. A delivery mechanism for vial working machines, comprising means for engaging the sides of the vials, means for engaging the ends of the vials, said means forming storage and cooling chambers, and means 85 for retarding the travel of the vials through said chambers, substantially as described.

9. A delivery mechanism for vial working machines, comprising a series of guide strips having their upper ends formed to cooperate 90 with said machines and receive finished vials therefrom and having their lower ends formed to provide pockets for said vials, and gauge strips cooperating therewith, substantially as described.

10. A delivery mechanism for vial working machines, comprising means for engagement with the sides of the vials, means for engagement with the ends of the vials, said means forming storage and cooling chambers for the finished vials, and a stripping finger cooperating with said means for forcing the vials through said chambers, substantially as described.

11. A delivery mechanism for vial working machines, comprising means for engaging the sides of the vials, means for engaging the bottoms of the vials, said means forming a storage and cooling chamber for the finished vials, means for forcing the finished vials through said chamber, and means retarding the travel of the vials therethrough, substantially as described.

12. The combination with a vial bottoming machine, of a delivery mechanism therefor comprising means for engaging the sides of the finished vials, means for engaging the bottoms of the finished vials, a stripping finger cooperating with said means for transferring the vials from the bottoming 115 machine to said means, and means for operating said stripping finger, substantially as described.

13. The combination with a vial working machine, of a delivery mechanism therefor, 125 said mechanism comprising opposed guide strips for engagement with the sides of the finished vials, means for adjusting certain of said strips, gauge strips for engagement with the ends of the finished vials, means 130

for adjusting the position of certain of said gauge strips, and means for transferring the finished vials from the vial working machine to said strips, substantially as described.

14. The combination with a vial working machine, of a delivery mechanism therefor, said mechanism comprising guide strips for engagement with the sides of the finished vials, a gauge strip for cooperation with the bottoms of the finished vials, said strips forming a chamber therebetween, a spring finger projecting into said chamber, and means for forcing the vials through said chamber against the action of said spring finger, substantially as described.

15. The combination with a vial bottoming machine having endless carriers pro-

vided with supports for the finished vials, of a delivery mechanism therefor, said mechanism comprising guide strips having their upper ends curved to cooperate with the vials in the bottoming machine, and having their lower ends curved to provide a vial pocket, means for adjusting the position of certain of said strips, gauge strips cooperating therewith, means for adjusting the position of certain of said gauge strips, and means for forcing the finished vials from the bottoming machine into engagement with said strips, substantially as described.

In testimony whereof, we have hereunto set our hands.

BENJAMIN T. HEADLEY.
DAVID IRVIN DU BOIS.
